UNITED STATES PATENT OFFICE.

HOMER A. KING, OF SPRINGFIELD, MASSACHUSETTS.

VELOCIPED.

SPECIFICATION forming part of Letters Patent No. 349,801, dated September 28, 1886.

Application filed June 8, 1886. Serial No. 204,535. (No model.)

To all whom it may concern:

Be it known that I, HOMER A. KING, a citizen of the United States, residing at Springfield, in the county of Hampden and State of Massachusetts, have invented new and useful Improvements in Velocipedes, which improvements are fully set forth in the following specification, the accompanying drawings making part of the specification.

10 My invention relates to improvements in bicycles, tricycles, and quadricycles; and it consists in an improvement for adjusting the point of attachment of propelling-straps to levers to increase the power or speed; in an improved 15 means of adapting the tricycle to turn corners or curves; in a new construction of hollow felly-rims, also bicycle frame and connections.

These improvements are described in connection with some of my improvements more fully 20 described in my Patents Nos. 327,397, 327,954, and 341,383, and applications filed January 20 and May 10, 1866.

Referring to the drawings, similar letters of reference indicate corresponding parts.

25 Figure 1 is a plan view of the tricycle shown in Fig. 2. Fig. 2 is a side elevation sectional view, being the right-hand side of tricycle, Fig. 1, taken on the broken line $x\ x$.

Fig. 3 is an enlarged view of one of the 30 levers and the means of increasing the speed or power by adjusting the point of connection to the levers. The flexible connection is attached to the link I, which is pivoted in the link I', which is pivoted on the lever so that 35 the lower part, when thrown backward, increases the leverage-power, and when thrown forward the speed is increased, and this change is effected by the forward or backward movement of the treadle R, which may be easily effected by the foot.

Fig. 4 is a top view of the tube J from the 40 fork of the steering-wheel to the point below the axle where the bracket t''' is attached to the perpendicular lever, t'''' , as shown in Figs. 2 and 5. The arm t'' is secured to the handle-bar shaft, which turns with the steering-wheel, and the ends of the bar t'' are connected by cords or wires t , either through the tube J or direct, as shown by broken lines, to the bracket at t'' , 45 which is caused thus to turn with the steering-

wheel, and the movement of the perpendicular lever t'''' moves the collar o , many-pointed at both ends, to the right or left, so that the drive-wheel on the inner part of the circle is always set at liberty, while the other drive-wheel propels the vehicle around the curve, and when the vehicle is moving in a direct line both ends of the collar o connect at both ends with the many-pointed collars, which revolve with the central continuous shaft, and the outer half-axles, to which the wheel-flanges are secured, all revolving together; but when turning a curve the continuous central axle turns within the loose wheel and its half-axle. A continuous tube-connection rod, as shown in Figs. 15 and 20, may be used in the tube J.

Fig. 5 also shows the tube J upon the tube J', which rests upon the springs N, and they upon boxes within which the separated axle revolves, and with but little friction, if my anti-friction adjustable spool-bearings are used, as shown in Fig. 6. A double set of movable ratchets should be used in the drums B and B', Fig. 5, and arranged to be shifted by a lever, so that one set of ratchets can be used to run 75 the tricycle forward and the other set to run it backward.

Fig. 7 shows the rollers F and F', used to roll 80 out the metallic hollow felly-rims shown in Figs. 8, 9, 10, 11, and 12, the broken lines indicating slight changes to be made to adapt the rolls to the different forms, all involving the same principle of constructing a hollow felly-rim from one piece of metal with central elevation, and uniting the parts by further 85 bending at v' and v'' and bringing the inner edges together, or one or both of the outer edges, by folding in and uniting them in a perpendicular or nearly perpendicular line and brazing or riveting them, both sides of the 90 metal being accessible at this point. The inner convex portion may be in waves or any other protuberant form. The side projections shown and described in the original application from the upper and outer part of the central elevation may also be constructed on this style longer than shown in the drawings, and with openings in the inner sides of the rubber tire, and thus the tire may be pressed in and held in place and from slipping.

My improved endless rubber tire is constructed with a protuberant outer surface and with an open surface on the inner side, and may have openings in the inner side of each 5 side projection, to be crowded over and fit the projections from the central elevation, and thus hold the rubber tire in place. In Fig. 8 the upright lines coming to a point indicate the form which they are in when the rim comes 10 from the rollers, and after being bent at v' and v'' , after riveting or brazing at the proper place, they are bent outward and formed into shape, then bent down as desired.

Fig. 13 shows the tricycle, Fig. 1, constructed 15 with one side like Fig. 14, with the small steering-wheel in the rear and in line with one of the large wheels. Fig. 14 shows one side of the tricycle used as a bicycle steered by the small wheel in the rear, the two wheels being 20 held at a fixed distance apart by the frame-section G, G', G'', G''', and G''''. The curved backbone or steering-shaft M is held in bearings at n'' and n''' , whether made as shown in Fig. 14 or made in sections, as shown, inclosed 25 in the curved case M', as shown in Fig. 15, whether with or without the rollers in the joint, as shown in Fig. 21. Fig. 14 also shows rear views of saddle.

A part of or all the bearings n , n' , n'' , and n''' 30 may be provided with my anti-friction roller-bearings. (Shown in detached views in Figs. 14 and 15.) The frame G, with saddle-spring support G', fulcrum branch G'', with or without a brace above or below, and branches G''' 35 and G, may be forged for both sides of the bicycle in one piece, or each side may be separate and united by bolts or otherwise at the bearings n'' and n''' . An upright steering-head may be used; but I prefer to have the 40 handle-bars connected directly and firmly to the steering-shaft M. The bearings n'' and n''' in Fig. 15 need not be in line, but when constructed as in Fig. 14 they should be in line or nearly in line with each other, and the 45 handles should be parallel or nearly parallel with a line passing through the bearings n'' and n''' , so that the depression of the right handle will turn the bicycle to the right, or the depression of the left handle will turn the bicycle to the left.

Fig. 16 shows my improved hub y , shown and claimed in a former application, with the following improvements, shown only in this application: The tube U''' is made with a shoulder, against which the frame may press at G''' 55 and united with or forming the inclined collar S''' for the inner bearing for the rollers S''; or the collar may fit over the tube U''', firmly or loosely against a shoulder on the tube, the 60 tube extending through the collar S''' and inward to form a loose parallel bearing in the hub to hold the wheel in place should the roller-bearings become misplaced, and enabling a person to tighten the roller-bearings 65 by turning the nuts on one or both ends of the axle U'''; but it is better to insert a washer between the outer end of the collar S''' and

the inner shoulder on the tube U''', or between the collar and the drum B; also, improvements in using the shaft U'' without nuts, and dispensing with the nuts heretofore used on the ends of shaft U', though it might be well to use one against which the screw-head U may be turned to act as a lock-nut; also, the improvement in the spring O''', made out of sheet-steel, with the points bent out for bearings or fulcra for the dog-connection O'', (shown also by a side view in Fig. 17,) which encircles the bearing of the drum B and is held, without screws, from turning by holes in it 80 fitting over pins headed in the partition-wall of drum B, the pivot-bearing of the spring holding the dog-connection O'', and its pressure against the drum B' holds the spring in place, so that the depression of lever E causes 85 drum B' to move backward and throw the dogs O'' into the ratchet O', and at the same time move drum B forward to propel the bicycle, and at the same time, by the shafts U' and U'' and the connections C, C', C'', and C''', 90 the drums and dogs on the other side are moved in the opposite directions, and the foot and lever on that side are raised ready to be depressed to propel the vehicle forward without a moment's loss of time. This connection 95 through the hub enables the rider to bear his weight upon the levers and utilize his weight as well as his muscle, and there being no weight upon these inner shafts this connection adds very little friction.

Fig. 18 is a top view of the handle-bars, and Fig. 19 is an enlarged view of the drum B' in Fig. 14 and its surroundings, though the brace G''' can be omitted and the bicycle be steered by the front wheel.

Fig. 20 is a front view of the branch G'', or lower part of the front fork, which may have a brace above or below to another part of the frame from the center or two ends of the fulcrum of the lever E.

Fig. 21 is a cross-section view of one of the joints of the steering-connection inclosed in the backbone M, Fig. 15.

Some of these improvements were described in the original application, filed January 20, 1886, Serial No. 189,181, which has been divided, this making case third springing from the original application, and I hereby disclaim in this application whatever is described and claimed in either of the other pending applications.

Having thus described my invention, what I claim as new, and desire to secure by Letters Patent, is—

1. In a tricycle propelled by levers with 125 flexible connection to propelling-drums, the treadle R, in combination with the eccentric I'' and connection with the eccentric I', and the link I, substantially as set forth, to change the point of connection with the lever to increase 130 the speed or power.

2. The centrally-located collar o, moved longitudinally on the central axle by means, substantially as set forth, by which the steering-

wheel operates the collar σ automatically, releasing the half-axle and its drive-wheel on the inner side of the circle in turning a curve.

3. The combination of the frame J with the tube J', springs N, and axle K, substantially as and for the purpose set forth.

4. A hollow felly-^{rim} constructed, substantially as set forth, from one piece of metal bent to form a protuberant surface toward the hub, and bent inward at v' and v'' , bringing the two surfaces together in a perpendicular or nearly perpendicular position when in the wheel, and united by brazing or riveting, and forming the rubber tire bed with a part elevated above the usual concave form.

5. A hollow felly constructed of one piece of metal with the edges united on the outside of the rim, between the outer sides of the side flanges, and in line or parallel or nearly parallel with a line running through the felly-rim and center of the hub of a wheel.

6. The bicycle-frame section G, G', G'', G''', and G''''.

7. In a bicycle steered by the smaller wheel in the rear of the driving-wheel, the combination of a bent, curved, or partly-curved steering-shaft held at or toward each end in a frame in bearings, and a handle-bar with arms bent

backward to bring the handles parallel or nearly parallel to each other, and parallel or nearly parallel to a line running through the bearings of the steering-shaft, so that the depression of the handle on the right will turn the bicycle to the right, or the depression of the left handle-bar will steer the bicycle to the left.

8. A bicycle steered by the smaller wheel in the rear of the driving-wheel, and having roller-bearings between the steering-connection and the bearings in the frame.

9. The combination of the hub y with the drums B and B', the tube U''', roller-bearings S'', frame G''', and nuts U''''', substantially as and for the purpose set forth.

10. The combination of the hub y, ratchet O', dogs O'', connection O''', spring O''''', and drums B and B', substantially as and for the purpose set forth.

11. The combination of the hub y, drums B and B', connections C, C', C'', and C''', with the screw U, shafts U' and U'', and connection to levers E, substantially as and for the purpose set forth.

HOMER A. KING.
